Primary Examiner — Rhea Shields(74) *Attorney, Agent, or Firm* — Carlson, Gaskey & Olds, P.C.**CLAIM**

The ornamental design for a CPAP device, as shown and described.

DESCRIPTION

FIG. 1 is a front-perspective view of a CPAP device, showing my new design;

FIG. 2 is a front view of the device of FIG. 1.

FIG. 3 is a rear view of the device of FIG. 1.

FIG. 4 is a right side view of the device of FIG. 1.

FIG. 5 a left side view of the device of FIG. 1.

FIG. 6 is a top view of the device of FIG. 1.

FIG. 7 is a bottom view of the device of FIG. 1; and, FIG. 8 is a front-perspective view thereof, shown in an environment.

In FIG. 8, the broken lines are for the purpose of illustrating environment only and form no part of the claimed design.

1 Claim, 3 Drawing Sheets(56)
